(57) **CLAIM**

The ornamental design for a faucet, as shown and described.

DESCRIPTION

FIG. 1 is a perspective view of a faucet showing our design;

FIG. 2 is a front elevational view thereof;

FIG. 3 is a rear elevational view thereof;

FIG. 4 is a left side elevational view thereof; the right side elevational view being a mirror image thereof; and,

FIG. 5 is a top plan view thereof.

The broken lines in the drawings represent unclaimed portions of the Faucet and form no part thereof.
